BEVERAGE BOTTLE CAP

Luke J. Strauss, Buffalo, N. Y.

Application October 24, 1934, Serial No. 749,843

6 Claims. (Cl. 225—22)

This invention relates to liquid dispensing devices and it has particular relation to the type of dispensing device which is detachable and applicable to containers which are adapted to be filled with liquid and sealed under gaseous pressure.

One object of the invention is to provide an improved device manually applicable and manually operable to break the seal of sealed liquid containers and to provide a controlled dispensing of the liquid contents of the container.

Another object of the invention is to provide an attachment suitable for use in connection with the dispensing of liquid contents from a container and in which a minimum number of parts are required, including deformable material which is yieldable in one direction to permit a puncturing element to puncture a cap of a sealed container, while it is yieldable in another direction to open a valve, whereby the liquid contents can be dispensed under controlled conditions.

In the drawing:

Fig. 1 is an elevation of a fluid container and a dispensing device incorporated therewith;

Fig. 2 is a vertical section, on a larger scale, showing in detail the structure of the dispensing device as incorporated upon a fluid container;

Fig. 3 is a vertical section similar to Fig. 2, and illustrating another form of device; and

Fig. 4 is a vertical section similar to Fig. 2, and illustrating still another form of device.

In practicing the invention a dispensing attachment 10 is shown mounted upon the upper portion of a fluid container 12, and includes a casing 13 having depending inwardly crimped flange sections 15. One or more of these sections is provided with an extension 16 to facilitate prying of the casing from the container. Shoulders 17 formed by crimping the flange sections 15 are adapted to snap below the lower flange edge 18 of a container cap 19, that is employed to seal the mouth 20 of the container.

A resilient annular washer 22 is disposed in the casing against its upper end wall 23 which is slightly spaced from the top of the cap 19. The spacing between the cap and end wall 23 is such that the washer is compressed when the flange shoulders 17 are snapped into position upon the lower edges of the cap 19.

A cup shaped portion 25 is pressed outwardly in the upper wall portion of the casing 10 and is provided with a central opening 26 through which a metallic sleeve 27 extends slidably and with so much play as to permit tilting or universal movement of the sleeve in the opening. The upper end

of the sleeve 27 has an outwardly and downwardly turned annular flange 28 which engages the upper end of a yieldable outer sleeve 30 composed of resilient material, such as compressible rubber. The lower portion on the rubber sleeve 30 rests upon the upper surface of the cup shaped portion 25 and the sleeve 30 is thus held under compression in such manner that it constantly tends to force the inner sleeve 27 outwardly from the casing. In order to prevent outward displacement of the sleeve 27, a valve member 32 is formed integrally upon the lower sleeve end and provides, together with the washer 33, a fluid tight closure for the casing opening 26. A series of lateral openings 35 are formed in the sleeve 27 adjacent the junction of the sleeve proper and its valve member 32, and provides for the passage of fluid through the sleeve when the valve member is opened. The lower end of the valve member has a downwardly pointed projection 36 located substantially at the center of the cap 19.

Upon mounting the casing 10 upon the container cap 19, the sleeve 27 can be manually forced downwardly, thereby compressing the resilient sleeve 30 and forcing the projection 36 through the cap 19 to form an opening 37 therein. Since this type of device is designed for application to fluid containers in which the fluid is sealed under pressure, the fluid is immediately released into the casing cap. As soon as the cap 19 is pierced, the fluid under compression in the container is free to pass into a chamber 38 formed by the casing, but the fluid is prevented from leaking by means of the washers 22 and 33. By manually holding the container, as indicated in Fig. 1, and tilting the sleeve 30 from its vertical position, or away from axial alignment with the container, the valve member 32 is unseated, or partially unseated; whereupon the fluid in the container is free to pass through the openings 35 and through the sleeve 27.

It is of course to be understood that in drawing fluid from the container, the user turns it to direct the mouth of the sleeve downwardly. That is, the container is turned after the manner of pouring fluid therefrom. The contents of the container can be directed into a drinking glass, or the like, under the influence of the gas under pressure which was stored in the container when the latter was filled. As soon as the sleeve 27 is released from its tilted position with respect to the container, the resilient sleeve 30 closes the valve member 32 against further discharge of the fluid.

In the form of the invention shown in Fig. 3, the sleeve 27 and casing 13 are substantially the

same in construction at those previously described, and hence, similar reference characters are employed to designate corresponding structural parts. In the construction shown in Fig. 3, however, the washer 33 is omitted, as such, and the lower end of the resilient sleeve 30 is formed with a lower flange 40 and adjacent groove 42 that receives the casing edge forming the opening 26.

10 When the sleeves 27 and 30 are tilted in the manner described above, the valve member 32 is unseated from one side of the flange 40 to permit the passage of fluid from the casing through the openings 35 and through the sleeve 27.

15 In this arrangement it is not necessary that the lower flange of the casing be crimped entirely about its circumference, but spaced sections 43 having shoulders 45 substantially the same as the sections 15 are provided to operate in substantially the same manner.

20 In Fig. 4, a portion 50 of the device which corresponds to the casing 13 is composed entirely of rubber, or other suitable resilient material, somewhat in the form of a nipple and is provided with an inner annular shoulder 52 which is resilient and can be stretched over the cap 19 until it is anchored upon the lower edges 18 thereof. A second annular shoulder 53 rests upon the marginal portion of the cap 19 and a cylindrical wall 30 55 joining these shoulders is slightly stretched and remains under tension while the shoulder 53 provides a seal about the cap.

25 The upper portion 56 of the resilient device 50, which is shaped like the rubber sleeve 30, is provided with an inner sleeve 57 formed of relatively rigid material and having at its upper end outwardly and downwardly turned flanges 58 engaging the upper end of the sleeve portion 56. A valve member 59 is screw-threaded in fluid-tight relation into the lower end of the sleeve 57 and is provided with a series of lateral openings 60 to serve the same purpose as the openings 35. The valve member is normally pressed into fluid-tight relation against an annular shoulder 62 of the 30 inner wall of the cap 50 and is provided with a lower pointed projection 63 which serves the same purpose as the projection 36 in puncturing the cap 19. In utilizing this construction the sleeve 57 is tilted in the same manner as that described above to unseat the valve member 59 from the shoulder 62, thereby providing free outlet of fluid from the interior of the casing through the sleeve 57.

35 From the foregoing description it will be apparent that the invention is adapted to be applied to any type of bottle, and although it is particularly adapted to be used in conjunction with a bottle having a sealing cap 19, it is apparent that the cap might be removed and the device used upon an ordinary unsealed bottle.

40 Although several forms of the invention have been shown and described in detail, it will be apparent to those skilled in the art that the invention is not so limited but that various changes may be made therein without departing from the spirit of the invention or from the scope of the appended claims.

I claim:

45 1. In a device for dispensing fluid contents from a sealed container having a cap sealed thereon, a chambered member having means for detachably securing it to the container cap, a tiltable member having a conduit for directing the flow of fluid from the container, said chambered member having an opening slidably and

55 tiltably receiving the tiltable member, a valve portion provided on the tiltable member for normally closing said opening in the non-tilted position of the latter member, cap puncturing means supported by the tiltable member to pierce the container cap in response to pressure applied to the last mentioned member, and resilient means engaging said members and yieldably maintaining the tiltable member against tilting movement and against sliding movement in the 10 opening of the chambered member.

2. In a device for dispensing fluid contents from a sealed container having a cap sealed thereon, a tiltable and axially movable sleeve, means for establishing communication from the interior of the container through the sleeve, resilient means engaging the sleeve to maintain it normally in a predetermined position, a puncturing element supported by the sleeve and movable to pierce the container cap upon axial movement of the sleeve against the resiliency of the resilient means, said first mentioned means including a valve member on the sleeve opening in response to tilting movement of the sleeve to control the flow of fluid from the container 25 through the sleeve.

3. In a device for dispensing fluid contents from a sealed container having a cap sealed thereon, a casing having means for removably securing it to the cap in fluid tight relation, a valve member tiltably mounted upon the casing and communicating through a wall thereof, said valve member having a puncturing element responsive to manual pressure to pierce an opening through the cap, resilient means normally 35 maintaining the valve member closed and yieldable to permit tilting of the valve member whereby communication is established from the container through the punctured cap and through the valve member while in tilted position.

4. In a device for dispensing fluid contents from a sealed container having a cap sealed thereon, a casing yieldably sprung over the cap in fluid tight relation therewith, a sleeve mounted in the casing wall in substantially axial alignment with the cap, said casing wall having an opening in alignment with the cap to receive the sleeve in slidable and tiltable relation, said sleeve having a valve portion normally closing the opening in the casing wall, resilient means engaging the casing wall and normally maintaining the sleeve in predetermined position and being yieldable to permit tilting movement of the sleeve, said sleeve having a puncturing element thereon responsive to pressure upon the sleeve to pierce the cap whereby fluid contents of the container 50 can be dispensed by tilting the sleeve to open the valve member.

5. In a device for dispensing fluid from a sealed container having a cap sealed thereon, a detachable resilient cap yieldable to slip over the container cap in fluid tight relation, a tiltable and axially movable sleeve mounted in the resilient cap in substantial alignment with the 65 container-cap receiving portion thereof and being normally yieldably held against tilting and axial movement by the resilient cap, a valve flange formed upon the sleeve and normally contacting an adjacent portion of the resilient cap 70 in fluid tight relation, said sleeve having openings for establishing fluid communication through the resilient cap in the tilted relation of the sleeve, and said sleeve supporting a piercing means responsive to pressure applied axially to 75

- the sleeve to puncture the container cap when the resilient cap is mounted thereon.
6. In a device for dispensing fluid from a sealed container having a cap sealed thereon, a detachable resilient cap yieldable to slip over the container cap in fluid tight relation, said resilient cap having shoulders for abutting the top of the container cap, said resilient means having an annular valve seat formed there-in, a tilttable and axially movable sleeve mounted in the resilient cap in substantial alignment with the container-cap receiving portion thereof and being normally held against tilting and axial movement by the resilient cap, a valve flange formed upon the sleeve and normally contacting the annular valve seat in fluid tight relation, said sleeve having openings for establishing fluid communication past the valve seat in tilted relation of the sleeve, and said sleeve supporting a piercing means responsive to pressure applied axially to the outer end of the sleeve to puncture the container cap when the resilient cap is mounted thereon. 5
